ARTICLE

Milton A. Hogan, P.O. Box 17, Ann Arbor, Mich.

Filed May 1, 1959, Ser. No. 55,731

Term of patent 14 years

(Cl. D35—2)

FIG. 2 is a right side elevational view thereof.

FIG. 3 is a transverse cross-sectional view thereof taken along line 3—3 of FIG. 1.

FIG. 4 is a transverse cross-sectional view thereof taken along line 4—4 of FIG. 1.

FIG. 5 is a transverse cross-sectional view thereof taken along line 5—5 of FIG. 1.

FIG. 6 is a front perspective view taken from the left side thereof on a reduced scale.

FIG. 7 is a fragmentary rear elevational view thereof.

The dominant features of my design reside in the portions shown in full lines.

I claim:

The ornamental design for a garden hand cultivator or similar article, substantially as shown and described.
